UNITED STATES PATENT OFFICE.

CHARLES D. KING, OF RUTHERFORD, NEW JERSEY.

PAPER FASTENER.

Application filed August 28, 1925. Serial No. 53,014.

To all whom it may concern:

Be it known that I, CHARLES D. KING, a citizen of the United States, residing at Rutherford, in the county of Bergen and State of New Jersey, have invented certain new and useful Improvements in Paper Fasteners, of which the following is a specification.

This invention relates to paper fasteners for use in holding flat files of papers, letters, documents, manuscripts, and the like, and particularly to paper fasteners embodying tongues to be pushed through the papers to be held and the projecting portions then bent down on the same, and of the type disclosed in my copending application Ser. No. 715,274 May 23, 1924. The main object of the invention is to provide improved means for covering the bent down portions of the tongues and preventing them from catching on adjacent objects such as loose papers, files and other things, and for preventing loose papers being caught and held or torn by them, particularly after such tongues have by continued use become bent and crooked so as to project sufficiently above the papers when the tongues are bent down on them.

The means I prefer to employ for accomplishing these objects together with other advantageous features of my improved paper fastener, are illustrated in the drawing accompanying and forming part of this specification, and in which—

Figure 1 is a plan of one form of my improved paper fastener applied to a file of papers.

Fig. 2 is a transverse section of the same taken on the line 2—2 of Fig. 1.

Fig. 3 is a perspective view of another form of the covering member for my improved paper fastener.

Fig. 4 is a top plan view of a paper fastener embodying the covering member of Fig. 3 as applied to a file of papers.

Fig. 5 is a plan of the underneath side of the covering member of Fig. 3.

Fig. 6 is a transverse section of the fastener and file of Fig. 4 taken on the line 6—6 of that figure.

Fig. 7 is a transverse section of the same taken on the line 7—7 of Fig. 4.

Fig. 8 is a longitudinal section of the same taken on the line 8—8 of Fig. 4.

Fig. 9 is a plan of this form of paper fastener in process of attachment to a portion of a file of papers.

Fig. 10 is a partial plan of another form of my invention attached to a portion of a file of papers.

Fig. 11 is a transverse section of the same taken on the line 11—11 of Fig. 10, and

Fig. 12 is a similar section of the covering member for this form of fastener.

Like characters of reference refer to like parts in all the figures of the drawing.

Referring to the drawing, the numeral 2 denotes a member provided with tongues such as 3, spaced apart and adapted to be bent up at right angles to the middle portion and then pushed through a file of papers such as 5, whereupon the projecting portions of the tongues and the ends thereof can be bent down on the topmost paper, thus holding and binding the papers together.

There is also a member 8, one form of which is shown alone in Figs. 3 and 5, which member is adapted to be placed over and cover the bent down portions of the tongues 3. The member 8 is provided with an underneath groove, channel or recess 9, preferably of the proper width and depth to allow the said bent down portions of the tongues to lie snugly therein. Near each end of the member 8 and adjacent to the bends of the tongues 3, are devices whereby the member 8 can be attached to the bent down portions of said tongues 3.

The said devices include members 15 preferably in the form of depending lateral tongues oppositely disposed near the ends of the covering member 8 respectively and adapted to be pushed under the bent down portions of the tongues 3. In the form shown in Fig. 1 there are also other members 16 which are in fact extremely short tongues that can be slipped under the edges of the bent down tongues 3 near the tongues 15 but on the opposite side so that there is a member 16 diagonally opposite to each of the members 15.

In the form shown in Figs. 3 to 7 inclusive the members 16 do not appear and in this form it is advantageous to form the groove or channel 9 with very little clearance so that the member 8 tends to be centered by the groove. In the first form however the clearance may be considerably more and also in the form shown in Figs. 10 to 12 inclusive. In Figs. 10 to 12 there is a lip or downward projection 17 opposite the point or free end of the lateral tongue 15 which tends to hold the member 8 in

place on the bent down tongue 3. It is released from said tongue portions when removing the member, by inserting a thin piece of metal underneath such as another member 8.

The operation of attaching the member 8 is partially illustrated in Fig. 9. After the tongues 3 have been bent down on the top-most paper of the file 5, the member 8 is placed over them in an oblique direction as shown in Fig. 9, so that one of the lateral tongues 15 can be pushed between a bent down tongue and the paper near the bend of the tongue. The other end of the member 8 is then moved laterally so as to push the other tongue 15 under the other bent down tongue near its bend. The lateral tongues 15 may be arranged each with an incline downward toward the point to facilitate their application under the bent down tongues. When the member is pushed laterally over the said bent down tongues, it is finally centered over them in some forms by a final snap action as the groove 9 suddenly slips into position on said tongue portions. In other forms the placing central is effected by observation on the part of the operator.

The above described mode of attaching the members 8 is very advantageous for the reason that the members 8 are held against the papers in a more balanced manner and so that all parts of the edges 11 thereof are in good contact with the top-most paper. If desired the member 8 may be slanted toward the edges to improve the contact when the member is applied to papers.

The device is particularly advantageous for use when the bent down portions of the tongues have been much used and are full of crooks and kinks and which condition is very objectionable with many tongue shields now in use. With my member 8 crooks and bends in the tongue portions tend to assist in keeping the member 8 more firmly in place as they tend to increase the holding pressure of the members 8 when placed over the bent down tongues with the lateral tongues 15 under such bent down portions.

What I claim is:—

1. A paper fastener embodying spaced apart tongues to be pushed through papers and the projecting portions bent down on the same, a member to be placed over and cover said bent down tongue portions, and means to secure said covering member to said bent down tongue portions which include two elements to be moved under them in relatively opposite directions.

2. A paper fastener embodying spaced apart tongues to be pushed through papers and the projecting portions bent down lengthwise of the fastener on said papers, a member to be placed over and cover said

bent down tongue portions, and means to secure said member to said bent down tongue portions which include two oppositely disposed elements which are movable into position under said portions in relatively opposite directions. 70

3. A paper fastener embodying spaced apart tongues to be pushed through papers and the projecting portions bent down on the same, a member to be placed over and cover said bent down tongue portions, and means to secure said covering member to said portions which include a plurality of elements to be moved under them, part of which elements are movable laterally under them in one direction and the other part of which elements are movable under them in the opposite direction. 75

4. A paper fastener embodying spaced apart tongues to be pushed through papers and the projecting portions bent down on the same lengthwise of the fastener, a member to be placed over and cover said bent down tongue portions and having a longitudinal groove in its under side in which groove the bent down tongue portions can lie, and means to secure said covering member to the bent down tongue portions which include two elements to be moved under them laterally from opposite sides and in 90 relatively opposite directions. 95

5. A paper fastener embodying two spaced apart tongues to be pushed through papers and the projecting portions bent down on the same, a member to be placed over and cover said bent down tongue portions and having an underneath groove in which the said bent down tongue portions can lie, and means to secure said member to said bent down tongue portions which include two laterally disposed portions movable under them in relatively opposite directions and adjacent to the bends of said bent down tongue portions. 100 105

6. A paper fastener embodying two spaced apart tongues to be pushed through papers and the projecting portions bent down on the same, a member to be placed over and cover said bent down tongue portions and having an underneath groove in which said bent down tongue portions can lie, and means to secure said covering member to said bent down tongue portions which include two lateral, depending tongues on said member and which by moving said member are adapted to be pushed laterally under said bent down tongue portions in relatively opposite directions, and means cooperating with said lateral tongues whereby the covering member can be centered over the bent down tongue portions. 110 115

7. A paper fastener embodying two spaced apart tongues to be pushed through papers and the projecting portions bent down on the same, a member to be placed

over and cover said bent down tongue portions and having an underneath groove in which said bent tongue portions can lie, and means to secure said covering member
5 to said bent down tongue portions which include two lateral, oppositely disposed, depending tongues on said member on opposite ends thereof which by moving said member laterally are adapted to be pushed
10 under said bent down tongue portions in

relatively opposite directions and two oppositely disposed cooperating portions whereby the covering member can be secured in position over said bent down tongue portions.

15

Signed at New York, in the county of New York, and State of New York, this 25th day of August, 1925.

CHARLES D. KING.
